UNITED STATES PATENT OFFICE.

WILLIAM ZABEL, DECEASED, LATE OF SWISSVALE, PENNSYLVANIA; BY BERTHA ZABEL, EXECUTRIX, ASSIGNOR TO THE UNION SWITCH & SIGNAL COMPANY, OF SWISSVALE, PENNSYLVANIA, A CORPORATION OF PENNSYLVANIA.

CIRCUIT CONTROLLER.

Application filed February 3, 1920. Serial No. 356,112.

To all whom it may concern:

Be it known that WILLIAM ZABEL, deceased, a citizen of the United States, late of Swissvale, in the county of Allegheny and State of Pennsylvania, did invent certain new and useful Improvements in Circuit Controllers, of which the following is a specification.

This invention relates to circuit controllers which are designed for operation by railway switches, and the function of which is to govern other apparatus in accordance with the positions occupied by the switch.

Certain forms of circuit controllers will be described embodying the invention, and then the novel features thereof will be pointed out in claims.

In the accompanying drawings, Fig. 1 is a view showing a railway switch, having one form of circuit controller C embodying my invention applied thereto. Fig. 2 is a vertical sectional view of the circuit controller C shown in Fig. 1. Fig. 3 is a plan view of the circuit controller with the cover removed. Fig. 4 is a vertical sectional view on the line IV—IV of Fig. 2. Fig. 5 is a view looking at the controller from the right hand side in Fig. 2, and showing only the cam 8 and crank 4, this view including a diagrammatic representation of the contacts to illustrate the contact operation when the cam shown therein is employed. Fig. 6 is a view similar to Fig. 5 but showing a different cam 8^a, this view also including a diagrammatic representation of the contacts for the same purpose as in Fig. 5. Fig. 7 is a view similar to the right hand portion of Fig. 1 but showing a modified form of circuit controller C^a having a crank 4^a of fixed length. Fig. 8 is a vertical sectional view of a cam 8^b adapted for use in the circuit controller C^a shown in Fig. 7. Fig. 9 is a view showing the cam 8^b in front elevation.

Similar reference characters refer to similar parts in each of the several views.

Referring first to Fig. 1, the reference character A designates a railway switch comprising as usual two fixed or stock rails 1 and 1^a, and two movable rails or switch points 2 and 2^a connected by a tie rod 2^b. Operatively connected with the movable rail 2^a is a circuit controller C, the operating connection comprising a rod 3 of adjustable length and a crank 4 of adjustable length.

It will be seen that reverse movements of the rails 2 and 2^a will cause oscillation of the crank 4 and so will cause operation of the parts connected to this crank within the circuit controller.

Referring now to Figs. 2, 3 and 4, the circuit controller C comprises a box 5 provided with a cover 5^a. One wall of the box 5 is provided with a bearing sleeve 6 in which a square shaft 7, provided with journals 25 and 25^a, is mounted to oscillate. The outer end of this shaft is attached to the crank 4 as hereinafter explained, and the inner end receives a cam 8 having a square hole as shown in Fig. 5. The cam is locked in place by a collar 26 attached to the shaft, and by a nut 27 screwed on the threaded inner end of the shaft. In the form shown in Fig. 5, the periphery of cam 8 is circular except for two notches 13 and 13^a, although as hereinafter explained other forms of cams may be employed.

The wall of box 5 which carries the bearing sleeve 6 is provided with two inwardly projecting lugs 9 and 9^a to which two contact operating arms 10 and 10^a are pivoted by means of pins 21 and 21^a. The arms 10 and 10^a are provided with rollers 11 and 11^a respectively which co-operate with the periphery of the cam 8 as hereinafter set forth. The arms 10 and 10^a are biased toward the cam by springs 12 and 12^a, respectively, so that the rollers 11 and 11^a follow the periphery of the cam as the latter oscillates.

The free ends of the arms 10 and 10^a actuate the electrical contacts which form part of the circuit controller. These contacts are carried by a block 14 of insulating material which is mounted transversely in the box 5. As here shown, four sets of contacts E, F, G and H are provided, each comprising two fixed contact springs 15 and 16, and a finger 17 movable into engagement with either spring. The contacts are arranged for operation in pairs, the two contacts E and F being operated by arm 10^a, and the two contacts G and H being operated by arm 10. To accomplish this, the movable fingers 17 of contacts E and F are connected by a block 18^a of insulating material which is provided with two vertically projecting pins 19^a, and these pins fit into slots 20^a in the forked end of arm 10^a.

The fingers 17 of contacts G and H are similarly connected by a block 18 having pins 19 which fit into slots 20 in the forked end of arm 10. It follows that by swinging arm 5 10 on its pivot 21 the fingers 17 of contacts G and H will be swung from springs 15 to springs 16 and vice-versa, and that contacts E and F are similarly actuated when arm 10^a is swung on its pivot 21^a.

10 The parts of the circuit controller and the connection therebetween and the switch A are so arranged that during a complete movement of the switch from one extreme position to the other the cam 8 is swung 15 through an arc of 70°, the crank 4 moving from a position 35° from the vertical on one side to a position 35° from the vertical on the other side. Referring now to Fig. 5, the two notches 13 and 13^a in cam 8 are 20 so located that when the switch is in the extreme position in which it is shown in Fig. 1, and which I will term the normal position, recess 13^a is opposite roller 11^a so that arm 10^a is swung inwardly toward the center of the cam 8, and that when the switch occupies its opposite extreme position, which I will term the reverse position, recess 13 is opposite roller 11, so that arm 10 is then 25 swung inwardly toward the center of the cam.

30 When the cam 8 shown in Fig. 5 is used, the operation of the apparatus is as follows: With the switch in the normal position, arm 10^a is in its inward position, so that contact 16—17 of each of the contact sets E and F is closed, and arm 10 occupies its outer position, so that contact 16—17 of each of the contact sets G and H is closed. As soon as the switch A moves away from 35 its normal position, arm 10^a is swung outwardly, thereby opening contact 16—17 of each contact set E and F and closing contact 15—17 of each of these sets. No further change occurs until the switch reaches 40 its reverse position, whereupon arm 10 swings inwardly, thereby opening contact 16—17 of each set G and H and closing contact 15—17 of each of these sets. During a movement of the switch from reverse to 45 normal position, contact sets G and H will be shifted as soon as the switch leaves the reverse position, and contact sets E and F will be shifted when the normal position of the switch is reached.

50 Referring now to Fig. 6, the cam 8^a is of such diameter that when the rollers 11 and 11^a are on the periphery thereof each contact finger 17 occupies a middle position wherein it is out of engagement with both 55 of the co-operating springs 15 and 16. When recess 13 registers with roller 11, however, the fingers 17 of contact sets G and H are moved into engagement with springs 15, and when recess 13^a registers 60 with roller 11^a the fingers 17 of contact sets

E and F are moved into engagement with the co-operating springs 16. The recesses 13 and 13^a are in this instance so located that they register with the rollers 11 and 11^a, respectively, when the switch is in the normal position, and the cam is provided with two lugs 22 and 22^a, which are so located as to register with the rollers 11 and 11^a, respectively, when the switch is in the reverse position. When lug 22 registers with 70 roller 11, arm 10 is moved to its outermost position wherein contact 16—17 of each set of contacts G and H is closed, and when lug 22^a registers with roller 11^a, arm 10^a is 75 swung to its outermost position so that contact 15—17 of each set of contacts E and F is closed.

80 The operation of the apparatus when the cam 8^a is provided, is as follows:

85 When the switch is in normal position, arms 10 and 10^a are swung to their innermost positions, so that the contacts are in the positions indicated directly above Fig. 6. As soon as the switch leaves the normal 90 position arms 10 and 10^a are swung to their intermediate positions wherein all of the contacts are open. When the switch reaches its reverse position, arms 10 and 10^a are 95 swung to their outermost position wherein contact 16—17 of each set G and H is closed and contact 15—17 of each set E and F is closed. The operation of the contacts during movement of the switch from reverse to normal position will be understood without further explanation.

100 The parts of the circuit controller are preferably so adjusted that when the cam notch 13 registers with roller 11, this roller is held away from the bottom of the notch by the engagement of the fingers 17 of contact sets G and H with springs 15. It follows, therefore, that when notch 13 registers with roller 11, any slight movement of the cam due to the passage of trains over the switch or to any other cause will not result 105 in engagement of the edges of the notch with the roller, and so will cause no wear of these parts. The same thing is true as to roller 11^a and notch 13^a, the roller in this instance being held out of engagement with the bottom of the notch by the engagement 110 of fingers 17 of contact sets E and F with fingers 16.

115 One important feature of this invention is the ratio between the radius of movement of roller 11 and the radius of movement of the forked end of arm 10 whereby a comparatively small movement of the roller by the cam causes a comparatively great movement of contact fingers 17. The amplitude 120 of movement is still further multiplied due to the fact that block 18 is comparatively close to the fixed end of each finger 17. It follows that a considerable contact opening 125 is secured with only a small movement of 130

roller 11 by the cam 8 or 8^a. The same thing is true as to arm 10^a, roller 11^a, and the contacts actuated thereby.

It will be seen from the foregoing that one set of contacts is operated when the cam is in one extreme position, and another set when the cam is in the other extreme position, and that the angular throw of the cam between these two positions is fixed. It follows that if the stroke of all switches were the same, the crank 4 could be made fixed in length, and when the circuit controller were applied to any switch the two sets of contacts would be operated in the two extreme positions of the switch. As a matter of fact, however, the throws of all switches are not alike, and so if the crank 4 were made fixed in length and the circuit controller applied to a switch for which it is not suited, the two sets of contacts could not be made to operate in the two extreme positions of the switch. For this reason I make the crank 4 adjustable in length, so that the desired angular throw of the cam may be secured regardless of the throw of the switch.

As here shown, the crank 4 is threaded to screw into one a threaded hole in one leg of an L-shaped member 23, the other leg of this member being clamped to the shaft 7. Two nuts 24 and 24^a are provided on the crank, one on each side of member 23, to lock the crank against turning after adjustment is effected. This means for adjusting the length of crank 4 is shown herein only for the purpose of illustration, it being understood that any other form of adjustable crank may be employed without departing from the scope of the present invention. One form of adjustable crank which is particularly well adapted to this use is shown and described in my co-pending application filed on even date herewith, Serial No. 356,111 for mechanical connections.

When the circuit controller shown in Figs. 2 to 5 is to be applied to a switch such as that shown in Fig. 1, the procedure is as follows: The circuit controller is first located and fixed in position beside the rails, and the length of the crank 4 is adjusted until the throw of the lower end thereof is approximately equal to the throw of the switch. The length of the rod 3 is then adjusted at 3^a so that when switch point 2 is tight against rail 1, the notch 13^a in cam 8 registers with roller 11^a. Finally, the length of the crank 4 is varied until it is such that when switch point 2^a is tight against rail 1^a, the cam notch 13 registers with roller 11. It will be seen, therefore, that the desired operation of the contacts can be secured, regardless of the throw of the switch, without any adjustment within the circuit controller C.

When the cam 8^a shown in Fig. 6 is used, the procedure in applying the controller to

a switch is substantially the same as that explained above, that is, the crank 4 is adjusted so that when the switch is in one extreme position the notches 13 and 13^a register with rollers 11 and 11^a, and that when the switch is in the other extreme position the lugs 22 and 22^a register with the rollers.

One important feature of my invention is the provision of a cam having a circular periphery with relatively short notches or lugs or both, whereby when a roller 11 or 11^a registers with one of these notches or lugs, only a small angular movement of the cam, corresponding to a very small movement of the switch rails such as $\frac{1}{8}$ inch, will suffice to swing arm 10 or 10^a enough to shift the contacts controlled thereby, this being true regardless of the direction in which the switch is moved. This insures that if the operating connection is so adjusted that a cam notch or cam lug registers with a roller when the switch is in an extreme position, a $\frac{1}{8}$ inch movement of the switch away from such position will cause a contact operation.

Another important feature of this invention is that the circuit controller can be turned around end for end without necessitating any change within the controller itself. Of course, when the position of the controller is thus changed, the contacts which were previously closed with the switch in normal position will be closed with the switch in reverse position. In the case of the cam shown in Fig. 5, this reversal of contact operation may be avoided by removing the cam and swinging the same around through an angle of 180°, whereupon the contact operation will be exactly the same as before the position of the controller was reversed. In the case of the cam shown in Fig. 6, the reversal of contact operation may be avoided by removing the cam and turning it face about on an axis passing through a diagonal of square shaft hole, bringing the lugs 22 and 22^a into the positions previously occupied by the notches 13 and 13^a, and vice-versa.

In some instances it may be desirable to make the operating crank fixed as to length, as shown in Fig. 7, and in such instances the cam must be made adjustable to compensate for switches having different throws. When such is the case, the cam 8^b shown in Figs. 8 and 9 may be employed. This cam comprises two cam sections 28 and 28^a, mounted on hubs 29 and 29^a, respectively, each hub having a square central aperture arranged to fit on the squared end of the shaft 7. The periphery of each hub is circular, and the corresponding cam section is arranged to fit freely thereon, so that the angular position of the cam section on its hub can be varied. To facilitate the angular adjustment of each cam section and to lock

it in adjusted position, the periphery of each hub is provided with a shoulder which lies against the side of the corresponding cam section, such shoulder being provided with gear teeth 30 or 30^a around a portion of its circumference, and each cam section carries a small gear 31 or 31^a which meshes with the teeth 30 on the corresponding hub. The gear wheel 31 is mounted to rotate on a screw 32 which passes into a threaded hole in cam section 28 and integral with this gear wheel is a hexagonal head 33 by which the wheel may be turned with a wrench. Gear wheel 31^a is mounted on cam section 28^a in a similar manner.

To change the position of cam section 28 on the hub 29, screw 32 is first loosened, and the cam section is then turned to the desired position by turning the gear wheel 31. The cam section is then locked in adjusted position by tightening screw 32. The procedure in adjusting cam section 28^a is the same.

The periphery of cam section 28 is provided with a notch 13, and the periphery of cam section 28^a is provided with a similar notch 13^a, which notches coact with rollers 11 and 11^a in the same manner as in Fig. 5. To prevent the periphery of cam section 28^a from interfering with the notch 13 in section 28, the periphery of section 28^a is provided with a recess 34^a extending from the point *a* in clockwise direction to the point *b*. For a similar reason the periphery of cam section 28 is provided with a recess 34 which extends from point *c* in clockwise direction to the point *d*. The depth of each of these recesses is at least equal to the depth of each notch 13 and 13^a, and the recess in each cam section is so located that for all adjustments of the cam in actual practice a portion of this recess will register with the notch 13 or 13^a in the other cam section.

The procedure in applying a circuit controller having the cam shown in Figs. 8 and 9 to a railway switch such as that shown in Fig. 1, is as follows:

The circuit controller is first fixed in place in the roadbed beside the switch and the cam sections 28 and 28^a are adjusted to approximately their proper relative positions. The rod 3 is then adjusted until its length is such that when switch point 2 is tightly closed against rail 1, the notch 13^a registers with roller 11^a. The cam section 28 is then adjusted to such angular position that when the switch point 2^a is tightly closed against rail 1^a the cam notch 13 registers with roller 11.

Although the cam shown in Figs. 8 and 9 is adjustable, yet when once adjusted so that the notches 13 and 13^a register with rollers 11 and 11^a in the extreme positions of the switch, a very slight movement of the switch away from either extreme posi-

tion will serve to raise one roller or the other out of the corresponding notch and so to actuate one set of contacts or the other. To express this point in another way, if the circuit controller is so adjusted that one set of contacts is closed when the switch is in normal position, this set of contacts will be opened by a movement of the switch greater than one-eighth of an inch from normal position.

Although there has been herein shown and described only a few forms of circuit controllers embodying this invention, it is understood that various changes and modifications may be made therein within the scope of the appended claims without departing from the spirit and scope of this invention.

Having thus described this invention, what is claimed is:

1. In combination, a railway switch, a circuit controller comprising a cam having a fixed stroke, two contacts controlled by said cam and actuated at the two ends of the stroke of the cam, respectively, and a crank of adjustable length connecting said cam and said switch whereby the fixed stroke of the cam may be secured with switches of different throws.

2. In combination, a railway switch, a circuit controller comprising a cam having a fixed stroke, a crank of adjustable length connecting said cam and said switch whereby the fixed stroke of the cam may be secured with switches of different throws, and two contacts actuated by said cam at the two ends of its stroke respectively, and consequently at the two ends of the throw of the switch.

3. A circuit controller for railway switches, comprising a cam mounted to oscillate, two contacts controlled by said cam and actuated respectively in the two extreme positions of the stroke of the cam, and a crank of adjustable length attached to said cam and adapted for connection with the switch whereby the stroke of said cam may be made the same for switches having different throws.

4. In combination, a railway switch, a cam operatively connected with said switch and having a uniform cam surface provided with an irregularity, a follower for said cam, and a circuit controlling contact actuated by said follower, said irregularity being of such length that if it registers with said follower when the switch is in one extreme position it will fail to do so upon a slight movement of the switch away from such position.

5. In combination, a railway switch, a cam operatively connected therewith and having a uniform cam surface provided with an irregularity, a follower for said cam, a contact controlled by said follower, and

means included in the connection between said cam and said switch for adjusting the connection so that said irregularity registers with said follower when the switch is in one 5 extreme position.

6. In combination, a railway switch, a cam operatively connected therewith and having a uniform cam surface provided with an irregularity, a follower for said 10 cam, a contact controlled by said follower, said irregularity and said cam follower being so proportioned that they register during only a small proportion of the total stroke of the switch, and means included in 15 the connection between said cam and said switch for adjusting the connection so that said irregularity registers with said follower when the switch is in one extreme position.

7. A circuit controller comprising a movable cam, an arm pivotally mounted at one 20 end, a cam follower located intermediate the ends of said arm, a movable contact finger mounted at one end, the free end of said arm being connected with said finger intermediate 25 the ends of the latter, and a fixed contact spring co-acting with the free end of said finger, whereby a given movement of said follower by the cam causes a considerably greater movement of the free end of said 30 contact finger.

8. A circuit controller comprising a movable cam having a uniform cam surface with a notch therein, a movable arm having a

follower coacting with said cam surface, a spring for biasing said arm and 35 follower towards the surface of said cam, a contact controlled by said arm and arranged to be closed when the follower registers with said notch, said parts being so proportioned that the biasing force of said 40 spring is overcome by said contact before the follower reaches the bottom of said notch, and that when the contact is closed a slight movement of the cam may occur without moving the follower, whereby such slight 45 movement causes no wear of the cam or of the follower.

9. A circuit controller comprising a horizontally disposed shaft mounted to oscillate, a cam attached to said shaft to oscillate in a 50 vertical plane and having a circular periphery provided with irregularities, two arms diametrically disposed on opposite sides of said cam and mounted to move towards and away from the center of the cam, each arm 55 having a follower coacting with the periphery of the cam, and two contacts one controlled by each of said arms.

In testimony whereof I affix my signature in presence of two witnesses.

BERTHA ZABEL,

*Executrix of the Estate of William Zabel,
deceased.*
